UNITED STATES PATENT OFFICE.

THOMAS MIDGLEY, JR., OF DAYTON, OHIO, ASSIGNOR TO THE NATIONAL CASH REGISTER COMPANY, OF DAYTON, OHIO, A CORPORATION OF OHIO, (INCORPORATED IN 1906.)

INDICATING MECHANISM.

1,181,239.

Specification of Letters Patent.

Patented May 2, 1916.

Application filed August 21, 1912. Serial No. 716,142.

To all whom it may concern:

Be it known that I, THOMAS MIDGLEY, Jr., a citizen of the United States, residing at Dayton, in the county of Montgomery and State of Ohio, have invented certain new and useful Improvements in Indicating Mechanism, of which I declare the following to be a full, clear, and exact description.

10 This invention relates to key operated cash registers and particularly to the differential mechanism of such machines and the connections for setting the indicators and actuating the counter therefrom.

15 Among the objects of the invention is to eliminate as far as possible the danger of overthrow of the counter pinions and indicators in machines of this class; to provide in such machines for adjusting oscillatory indicator units from one position directly to any other without first returning them to a constant position; to provide a positive stop for the indicators when the latter reach positions determined by the keys, and 20 through the positive limiting means for the indicators a similar stop for the counter actuators and through them the counter pinions; and to provide mechanism whereby when no key of a denominational set is depressed the operation of the machine by depression of a key in another denominational set will serve to insure the indicator for the set in which no key is depressed indicating zero after the operation.

25 Briefly the above objects are accomplished in the embodiment herein disclosed by mounting for coöperation with the keys of each denominational set two frames stepped complementarily, corresponding steps of

30 which coöperate with the respective keys when the latter are depressed to be moved differentially thereby. One of the frames of each set is provided with gear teeth for actuating the corresponding counter pinion

35 and this frame is elevated differentially by the keys in accordance with the numerals on the keys by means of the stepped arrangement of the frame differentially to operate the counter pinion. The other frame being

40 stepped complementarily to the counter actuating one is elevated the complement of the extent the first mentioned one is elevated. Both of these frames pivotally carry links the opposite ends of which have pins

45 playing in arcuate slots in oscillatory disks toothed on a portion of their periphery to engage with pinions on their indicator units which are thus adjusted in accordance with the adjustment of the disks. When the indicators are at zero the pins on the links 50 are at the forward ends of their arcuate slots and differential adjustment of the link connected with the counter actuating frame will, by its pin engaging the upper end of its slot in the disk, rotate the latter and the 55 connected indicator in accordance with the movement of the frame which actuates the counter pinion. The pin on the other link being on the opposite side of the axis of the disk, when elevated will move rearwardly 60 and upwardly with respect to its slot until the desired adjustment of the disk results, when it is then in engagement with the upper end of its slot and positively prevents any further movement of the disk and its 65 connected indicator. When the indicator is to be adjusted from a lower to a higher position it is moved by the link connected with the counter actuating frame and the other link positively limits the movement of 70 the disk while if the indicator is to be adjusted from a higher to a lower position the movement is accomplished by the other link and frame which moves the indicator disk reversely to proper position the first mentioned link limiting the reverse movement 75 of the disk and indicator. The lengths of the slots correspond to the distance the indicator disks move in going from their zero 80 to their "nine" positions, and at the moment 85 an adjustment of an indicator is completed the pins on the links are always at the upper ends of their slots.

To provide for adjusting the indicators to zero when no key of their corresponding 90 sets is depressed, a member taking the place of a zero key is provided for each set of keys, which is normally in the path of the key coupler but is withdrawn from such path whenever a key of its set is depressed and 95 coupled with the key coupler. This member coöperates with the stepped frames so as to not move the counter actuating one, but to move the other frame nine steps which thus insures the return of the indicator and disk 100 of one set of keys to zero position whenever the machine is operated with no key of the set depressed.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Figure 1 is a vertical section through the machine taken on the irregular line *a*—*a*, Fig. 2, looking in the direction of the arrows and showing the tens set of keys and the connections with their indicator and counter elements. Fig. 2 is a longitudinal section of the machine taken on the line *b*—*b*, Fig. 1.

In the drawings 1 represents the end frames of the machine which are connected by longitudinal bars 2, 3 and 4 near the front, bottom, and rear portions of the frames respectively, and by longitudinal shafts 5 to 10 hereinafter more particularly referred to. Upon the shaft 5 are pivoted the key levers 11 through which the power for operating the machine is transmitted, and of which there are shown three sets of nine each. The rear portions of these keys normally rest on the bar 3 and their rear ends are notched at 13 and curved at 14 for coöperating with a key coupler rod 15 carried by arms 16 pivoted at 17 to the inner sides of the end frames. Alongside the "one" key lever of each set is a link 18 also normally resting on the bar 3 and notched and curved at its rear end like the corresponding ends of the levers 11 and for coöperating with the key coupler rod 15. The links 18 do not extend forwardly as far as the key levers 11 but their forward ends are loosely mounted on rods 19, of which there is one for each set of keys. These rods 19 are supported at each end by arms 20, the lower ends of which are loose on the shaft 5. Springs 21 connect at their ends with these links and with the shaft 7 and normally hold the links rearward in the position shown. The rods 19 normally lie against the forward sides of hooks 22 projecting upward just above the shaft 5 from the keys 11 and whenever a key is depressed at its forward end, through its hook 22 it carries the rod 19 and the zero link 18 of its set forward so that the rear portion 14 of the link will clear the key coupler rod 15 and allow the latter to be raised without being lifted thereby. In case no key of a set is depressed to move the link 18 of that set of keys forward as just described, the key coupler rod when rocked upward by engagement in the notch 13 of a key in another set which is depressed will, by contacting with the lower end of the curved portion 14 just above the notch 13 of the link, raise the latter which, by coöperating with the

stepped frames, returns the indicator unit of that set to indicate zero in a manner hereinafter described.

The rear ends of the keys and links 18 co-operate with the complementarily stepped frames 23 and 24 carried at each end by arms 25 and 26 loosely mounted at their forward ends on the shaft 5. Projections 49 depend from the forward ends of these arms beneath the shafts 5 and normally bear against the rear side of the shaft 6 which thus serves to support the arms and frames in the normal position shown. These frames have on their under sides ten graduated steps, one for each of the nine keys and one for the link 18 of each set. They are stepped complementary to each other so that when a key or link is elevated against them from beneath, the sum of the extents of movements of the two frames, considering steps as a unit, will always equal nine. The frames 23 are the ones which actuate the counter pinions and these are always elevated distances corresponding to their depressed keys, while the rear frames 24 are always elevated extents corresponding to the difference between the number of steps their corresponding frames 23 move and nine. The left or nine key of a set will move its frame 23 upwardly nine steps and the frame 24 none; the next or eight key moves the frame 23 eight steps and frame 24 one; the seven key moves the frame 23 seven steps and the frame 24 two, and so on. The link 18 is at the right of the units key of a set and when elevated does not move the frame 23 at all but elevates the rear frame 24 nine steps. When the rear end of a key or link is completely elevated its upper side is always in engagement with corresponding complementary steps on the lower sides of both of the frames 23 and 24.

From the above description it will appear that the frames 23 are always elevated differentially in accordance with the keys depressed. This differential movement is used to actuate the counter pinions in accordance with the keys depressed and to this end the left hand one of the arms 25 carrying these frames have upward extensions 27 provided with gear teeth, and by rocking the counter 28 carried by arms 29 pivoted on studs 30 of the machine frames downward to engage the counter pinions 31 with the gear teeth of the extensions 27, holding them in engagement while the frame 23 and arm 25 are being elevated and disengaging them before the return of the frames, the counter pinions will be actuated differentially in accordance with the keys depressed. The means for engaging the counter with its actuators as well as the transfer mechanism for it forms no part of the present invention and are common in the art and need not be described in this application.

The frames 23 and 24 pivotally connect at 32 and 33 respectively with the lower ends of links 34 and 35. These links respectively have pins 36 and 37 at their upper ends 5 which play in arcuate slots 38 and 39 of indicator actuating disks 40 loosely mounted on the shaft 9. These disks 40 have teeth 41 on a portion of their periphery meshing with pinions 42 rigid with oscillatory indicators 43 carried by longitudinal shaft 10 whereby differential adjustment of the disks 40 similarly adjusts the indicators. The indicator actuating disks 40 also have notches 44 for coöperating with pawls 45 mounted 10 upon shaft 8 and normally held in locking engagement with the notches by springs 46 mounted between them and the longitudinal bar 4. The pawls 45 under tension of their springs normally hold the disks and connected indicators in adjusted position but 15 can yield to permit adjustment of the indicators when the machine is operated.

The position of the indicators shown in the drawings is their zero position and that 20 of the disks 40 their normal position. With the indicators and disks 40 in zero position pins 36 and 37 of the links rest against the forward ends of their slots 38 and 39. Upon depression of a key the frame 23 will be elevated to an extent dependent upon the key 25 depressed and this frame through its link 34 engaging the forward end of the forward slot 38 will swing the disk 40 clockwise to an extent corresponding to the amount of 30 elevation of the frame 23 and set the connected indicator 43 accordingly. At the same time the link 35 connected with the rear frame 24 is with its frame elevated an extent equal to the complement of the movement of the other frame and link and this 35 carries pin 37 of this link, it being to the rear of the axis of the disk while the pin 36 of the link 34 is to the front of the axle, upwardly and rearwardly in a direction reverse 40 to the movement of the disk. This upward movement of the link 35 is just sufficient to positively stop the disk from clockwise movement at the moment the upward movement of the links is concluded. The slots 38 and 39 are of just sufficient length to permit 45 their pins having nine degrees of movement in them in passing from one end to the other. After the indicators and their actuating disks are adjusted the pawls 45 retain 50 them in such adjustment while the links 34 and 35 fall with their frames 23 and 24 to the positions shown in the drawings. The positions of the pins 36 and 37 in their slots after an operation may be any of ten different 55 positions dependent upon the keys last depressed and the consequent setting of the indicators and their actuating disks 40.

The indicators are always adjusted from one position directly to another and it is apparent that, when they are moved from

lower to higher positions, the links 34 in raising effect the movement by engaging the upper ends of the forward slots 38, the pins 37 on the links 35 serving then to positively limit their movement by engaging 70 the rear ends of their slots 39 at the moment of completion of the adjustment of the indicators, while when the indicators are to be adjusted from higher to lower positions they are moved in the reverse direction by pins 37 75 on the links 35 the complement of the extents indicated by depressed keys engaging the upper ends of the slots 39, the pins 36 on the links 34 in such cases serving to positively limit the movement of the actuating 80 disks the moment they reach positions according to the keys depressed. The arrangement of the slots, links, and actuating frames is such that whenever any adjustment of an indicator is completed the pins 36 and 37 85 of its actuating links are always against the upper ends of their slots, and as these links are in opposite sides of the axis of the disks and are both moved upward, they tend to impart movement to the disk in opposite directions with the result that no further movement of the disks takes place in either direction.

It will be remembered that there are but 90 nine keys in a set, but that an additional link 18 is provided which is elevated whenever the machine is operated and no key of its set depressed. This elevation of the links 18 does not elevate its frame 23 and link 34, but elevates its frame 24 and link 35 nine 100 steps, which results in the complete elevation of the pin 37 in its slot 39 to positively return its indicator disk 40 counter-clockwise to carry its indicator to zero if it had been left otherwise by the preceding operation.

Front and rear indicators are provided in the machine as shown, those indicating at the front appearing at the left in Fig. 2, while the three right hand ones in this figure 110 are for rear indication. The two outside indicators are for the hundreds denomination and are carried by the indicator shaft 10 which is rotated by a pinion 42 mounted on the shaft near its left hand end and meshing with the gear teeth 41 on the indicator actuating disk adjusted by the set of keys for the hundreds denomination. The shaft 10 loosely carries intermediate the units indicators a sleeve 47 which carries 115 near its ends the front and rear indicators for the tens denomination. Adjacent the front indicator near the left hand end of this sleeve, the latter rigidly carries the pinion 42 engaging with the tens denominations 120 indicator actuating disk. Surrounding the sleeve 47 between its indicators is still another sleeve 48 which carries at its ends the units indicators and adjacent the right one of these is the pinion 42 meshing with the 125

indicator actuating disk for the units set of keys. By this construction both the front and rear indicators are similarly adjusted when the machine is operated to indicate

5 both at the front and the rear, the amount entered in the counter.

To operate the machine the proper keys of the necessary denominational sets are slightly depressed to couple them with the 10 key coupler by engaging their notches 13 over the key coupler rod 15. The last key to be depressed is forced all the way down which, through the elevation of its rear end, completely raises the key coupler and 15 through it those keys previously coupled with it by slight depression only. The depression of a key in a set withdraws the zero link 18 of that set from the path of the key coupler rod 15 to allow raising of the latter 20 without affecting the zero link. If no key in a set has been depressed the zero link 18 of the set is left in rearmost position and elevation of the key coupler by depression of a key in another set will elevate such link. 25 The elevation of the rear ends of the keys and links raises the stepped frames, the counter actuating one always in direct proportion to the value of the depressed keys, and this upward movement of this frame 30 through the gear teeth on the extension 27 accordingly actuates the counter. The frames 23 and 24 through their links 34 and 35 serve to set the indicator disks directly from one position to another, the former 35 positively moving the disk to set the indicator from lower to higher positions, and the latter positively moving the disks in the reverse direction when the indicators are moved from higher to lower positions. 40 When one of the links actually moves the indicator actuating disk the other moves sufficiently to position its pin so that at the moment the first mentioned link completes its adjustment of the indicator disk the pin 45 of the other engages with the upper end of its slot in the disk and prevents further movement of the disk. The weight of the key coupler and the sets of frames is sufficient to lower them and the rear ends of the 50 keys to restore the keys to operable position.

While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the 55 claims which follow.

What is claimed is:

1. In a cash register, the combination of a totalizer; actuators therefor, indicators, actuators for the indicators, the totalizer 65 actuators and indicator actuators perform-

ing their functions simultaneously, and connections whereby the indicator actuators prevent overthrow of the totalizer actuators and totalizer.

2. In a cash register, the combination of 70 a counter pinion; a differentially movable frame for actuating the same; an indicator connection from the frame to the indicator whereby the former may set the latter; and differentially movable means for positively 75 preventing further movement of the indicator after it reaches the position corresponding to the differential movement of the frame.

3. In a machine of the class described, 80 the combination of a counter a differentially movable counter actuating frame; a second differentially movable frame; means for actuating the frames to complementary extents; an indicator; and connections between 85 the frames and the indicator whereby the latter is adjusted to indicate the extent of movement of the counter actuating frame by moving directly from one position to another. 90

4. In a machine of the class described, the combination of a plurality of movable frames; a series of keys for actuating the same; steps on the frames complementarily arranged for coöperating with corresponding keys for actuation to complementary extents thereby; an indicator; and connections whereby the movement of the frames can adjust the indicator in opposite directions, the direction of movement of the indicator 100 by the connections being dependent upon the position of the indicator before the beginning of the operation.

5. In a machine of the class described, the combination of a plurality of complementarily stepped movable frames; a series of operating means for the frames for engaging complementary steps on them to actuate the frames differentially; an indicator actuating disk; and oppositely effective one way 105 driving connections between the frames and the disk for adjusting the indicator from one position directly to another. 110

6. In a machine of the class described, the combination of a plurality of complementarily stepped movable frames; a series of operating means for the frames for engaging complementary steps on them to actuate the frames differentially; an indicator actuating disk having a plurality of arcuate 115 slots; and links pivoted at one end to the frames and having pins at their other working in their corresponding slots in the indicator actuating disk, the relationship of the disk and pins being such that the movements of the latter are in opposite directions about the axis of the disk and the arrangements of the slots such that but one of the links is effective to rotate the disk at a 120 time. 130

7. In a machine of the class described, the combination of a differentially movable frame; operating mechanism therefor; a second frame adapted to be moved by the operating mechanism to extents complementary to the movements of the first mentioned frame; indicating mechanism; and connections between the frames and the indicating mechanism whereby the first mentioned frame adjusts the indicator from lower to higher positions and the last mentioned frame adjusts it from higher to lower indicating positions.

8. In a machine of the class described, the combination of a differentially movable frame; operating mechanism therefor; a second frame adapted to be moved by the operating mechanism to extents complementary to movements of the first mentioned frame; and connections whereby either the first mentioned frame adjusts the indicator from lower to higher position to indicate the extent of movement of the frame, or the second mentioned frame adjusts the indicator from higher to lower position to indicate the extent of movement of the first mentioned frame.

9. In a machine of the class described, the combination of a differentially movable frame; operating mechanism therefor; a second frame adapted to be moved by the operating mechanism to extents complementary to movements of the first mentioned frame; an indicator; an actuating disk therefor; connections between the first mentioned frame and the indicator actuating disk for moving the latter in one direction; and connections between the other frame and the indicator disk for moving said disk in the opposite direction, the effectivity of the connections upon the disk being determined by the position of the disk at the beginning of the operation and the position it is to occupy at the end of an operation.

45 10. In a machine of the class described, the combination of an accounting mechanism; a plurality of devices connected thereto for operating the accounting mechanism in opposite directions effective on the accounting mechanism in one direction of their movement only; and means for moving the devices to complementary extents to adjust the accounting mechanism from one position directly to another.

55 11. In a machine of the class described, the combination of an accounting mechanism; a plurality of devices connected thereto for operating the accounting mechanism in opposite directions effective on the accounting mechanism in one direction of their movement only; and means for moving the devices to complementary extents to adjust the accounting mechanism from one position directly to another, the device not serving to adjust the accounting mechanism

serving as a positive stop for the latter when it reaches adjusted position.

12. In a machine of the class described, the combination of accounting mechanism; a series of keys; a plurality of devices movable differentially by the keys and complementary to each other; and pin and slot connections between the devices and the accounting mechanism whereby either may adjust the accounting mechanism to a position corresponding to the depressed key while the other serves as a stop to prevent movement of the accounting mechanism beyond its desired position.

13. In a mechanism of the class described, the combination of accounting mechanism; manipulative mechanism; and a plurality of devices having a normal position and connecting said mechanisms for actuating the former from the latter and for limiting such actuation, one of the devices serving to limit the actuation of the accounting mechanism when the other is actuating it.

14. In a machine of the class described, the combination of an actuating disk for accounting mechanism having a plurality of arcuate slots therein; pins mounted in the slots and normally separated angularly about the axis of the disk by a constant angle; and means for changing the angular distance between the pins to set the accounting mechanism.

15. In a machine of the class described, the combination of a plurality of indicators; a plurality of sets of keys for operating the same; a key coupler and connections whereby it is coupled with the keys by a slight depression of the latter; a zero bar for each set normally coupled with the key coupler whereby operation of the key coupler by a key of another set will operate the zero bar to restore its indicator to zero; and means whereby the depression of a key of a set disconnects the zero bar of such set from the key coupler.

16. In a machine of the class described, the combination of a main operating mechanism an indicator; a series of keys for adjusting the same; a member normally in position to restore the indicator to zero upon the operation of the operating mechanism; and means whereby the member is withdrawn from normal position when the indicator is to be adjusted by the depression of a key in the series.

17. In a machine of the class described, the combination of a plurality of indicators; a plurality of sets of keys for setting the same; means for restoring the indicators to zero when the machine is operated without the depression of a key in their sets; and means whereby the last mentioned means of any set is disabled when a key in such set is depressed.

18. In a machine of the class described,

- the combination of a main operating mechanism, an indicator; a series of keys for controlling the adjustment of the same to indicate other than zero; connections whereby the indicator is adjusted to indicate zero when the operating mechanism is operated without the depression of a key; and means whereby the connections are disabled when a key is depressed and the indicator adjusted in accordance with it.
19. In a machine of the class described, the combination of a plurality of indicators; a plurality of sets of keys for adjusting the indicators to indicate other than zero; means for adjusting the indicators to zero when the machine is operated without the depression of a key in their corresponding set; and means whereby the depression of a key to set an indicator disables the last mentioned means for that indicator.
20. In an indicating mechanism, the combination of an indicator; means for adjusting the latter from one position directly to another; a series of keys for differentially operating said means; connections for operating said means to adjust the indicator to zero position when the machine is operated without the depression of a key; and projections carried by the keys for disabling the connections when the key is depressed.
21. In an indicating mechanism, the combination of an indicator actuating disk; a plurality of links connected thereto for rotating the disk in either direction to adjust the latter from one position directly to another; a series of keys for moving the links differentially and complementary to each other; a zero bar adapted to operate the links to restore the indicator disk to zero when the machine is operated without the depression of a key; a pivotally supported rod connected with the zero bar and passing over the keys; and projections on the keys for engaging the rod when a key is depressed for moving the bar to render it inoperative when the indicator is to be adjusted by the depression of a key.
22. In an indicating mechanism, the combination of an oscillatory indicator actuating disk provided with arcuate slots; a plurality of links having pins working in said slots and normally separated a constant angular extent; and means for changing the angular distance between the pins to a constant extent at each operation to adjust the indicator, the final adjustment of the same depending upon the relative extents of movement of the pins on the links.
23. In an indicating mechanism, the combination of an indicator actuating disk; a plurality of links connected therewith but movable relatively thereto; and key controlled means for changing to a constant extent at each operation the angular dis-
- tance between the points of connection of the links with the disk, the construction being such that the links are given various relative extents of movement dependent upon the keys depressed, to determine the final adjustment of the indicator and the direction in which it moves in its adjustment.
24. In a cash register, the combination of a counter pinion; a differentially movable frame for actuating the same; an indicator; connections from the frame to the indicator whereby the former may set the latter; and differentially adjustable means for positively limiting the adjusting movement of the indicator when it reaches the position corresponding to the differential movement of the frame.
25. In an accounting machine, the combination of a series of keys; an indicator; and a plurality of connections between the keys and the indicator, movable differentially and independently by the keys, for adjusting the indicator and limiting its movement, the construction being such that when either of the connections adjusts the indicator the other limits the movement of the latter.
26. In a machine of the class described, the combination of an accounting mechanism; a series of keys; a plurality of devices movable differentially by the keys and complementary to each other; pin and slot connections between the devices and the accounting mechanism whereby either may adjust the accounting mechanism to a position corresponding to the depressed key while the other serves as a stop to prevent movement beyond its desired position, the pin and slot connections being constructed to permit the differentially movable devices to be returned to normal position; and means for locking the accounting device in adjusted positions.
27. In a machine of the class described, the combination of an actuating disk for accounting mechanism and having a plurality of guiding surfaces; pins mounted in co-operative relationship with said guiding surfaces; links carrying said pins and normally nearly parallel; and means for bodily moving said links, said guiding surfaces being constructed to change the angular distance between the links to varying extents to cause said pins to always move the same linear distance apart whereby said actuating device is set.
28. In a machine of the class described, the combination of two complementary stepped movable frames; an indicator; a series of operating means for the frames for engaging complementary steps on both of them and then moving the same differentially; and connections between the frames and the indicator for moving the latter.
29. In a machine of the class described,

- the combination with a plurality of complementary stepped movable frames; an indicator; operating means for engaging all of said frames and moving them differentially while in engagement therewith; an indicator actuating disk; and connections between the frames and the disk for adjusting the indicator from one position directly to another upon movement of said frame.
- 10 30. In a machine of the class described, the combination with an indicator, of a bank of keys for each indicator, a pair of elements for each bank of keys arranged to be given complementary differential movements by operations of the keys, connections whereby the movement of one element will differentially drive the indicator and the movement of the other element will differentially move a stop for the indicator.
- 20 31. In a machine of the class described, the combination of a plurality of complementary stepped movable frames, a series of operating devices arranged to engage complementary steps on the frame to operate both frames differentially, an indicator, an indicator actuator, and oppositely effective connections between the frame and the actuator, one connection moving the indicator directly from its position of previous adjustment to the desired position and the other preventing movement of the indicator past said desired position.
- 30 32. In a cash register, the combination with an accounting element, and dual means operable singly to actuate said accounting element, said dual means being so constructed that each of said means will act to limit the actuation of said element when the other of said means is actuating said element.
- 40 33. In a cash register, the combination with an accounting element, and dual means operable singly to actuate differentially said accounting element, said dual means being so constructed that either of said means will act to limit the actuation of said element when the other of said means is actuating said element.
- 50 34. In a machine of the class described, the combination with a plurality of indicators, of a set of depressible keys for each indicator, a pair of elements for each set of keys arranged to be given complementary differential movements by operations of the keys, connections whereby said movements will differentially move the indicator in either direction and positively limit the extent of movement, and other connections whereby depressing a key in any one set will position the indicators of the other sets at zero.
- 60 35. In a machine of the class described, the combination with a plurality of indicators, of a set of keys for each indicator, means for coupling together for simultaneous operation keys of different sets, said means being given an invariable extent of movement at each operation, and means whereby said coupling means will position at zero the indicators for the sets in which no key has been connected to the coupler.
- 70 36. In a machine of the class described, the combination with a plurality of indicators, of a bank of keys for each indicator, a pair of elements for each bank of keys arranged to be given complementary differential movements by operations of keys in the bank, connections between each element and the indicator whereby the movement of one element will differentially move the indicator and the movement of the other element will differentially move a stop for the indicator, an element given an invariable extent of movement when the machine is operated, and means automatically coupling one of the aforesaid elements to the invariably moved element when no key in a bank is depressed whereby to set the indicator for that bank at zero.
- 80 37. In a cash register, the combination of a totalizer, actuating mechanism therefor, indicator actuating mechanism, and connections whereby the indicator actuating mechanism prevents both overthrow and rebound of the totalizer actuating mechanism and totalizer.
- 90 38. In a cash register, the combination of a totalizer, actuating mechanism therefor, indicator actuating mechanism, and oppositely effective connections whereby the indicator actuating mechanism prevents both overthrow and rebound of the totalizer actuating mechanism and totalizer.
- 100 In testimony whereof I affix my signature in the presence of two witnesses.
